REMOTE POSITIONING MEANS

Fritz Frederick Uehling, Passaic, N. J.

Application March 3, 1942, Serial No. 433,269

11 Claims. (Cl. 172—239)

This invention relates to improvements in remote positioning means, one object of the invention being to energize a motor of any conventional type to function in one direction or the other as required to change the position of any element located at some remote point in accordance with changes in the position of another element at some local point. Another object of the invention is to provide means for actuating the motor at a velocity in proportion to the distance which the remotely positioned element must move in order to assume a position corresponding to that of the local element, thus reducing the speed of the motor gradually while the remote element is approaching said corresponding position until, when said corresponding position has been reached, the speed of the motor will have been reduced to zero. By thus reducing the speed of the motor progressively the possibility of overstepping is eliminated thereby preventing any hunting action which, due to the inertia of the motor, would otherwise take place. Still another object of the invention is to provide sufficient power input to the motor to insure a high driving torque regardless of the speed at which the motor may be operating, thereby insuring a strong motor torque regardless of how minutely the position of the remote element may differ from the position of the local element.

Figure 1 illustrates diagrammatically all of the elements of the invention with their electrical connections, and Figure 2 illustrates diagrammatically the geared connection through which the remotely positioned element is actuated by the motor.

A reversible motor 1, Figure 2, consisting of an armature 2 and two field windings 3 and 4, as illustrated diagrammatically in Figure 1, is in geared connection with the brush 7 of a potentiometer 5—6 as illustrated in Figure 2. The motor is electrically connected through fixed contact pieces 8 and 9, and a movable contact member 10, Figure 1, so that, when contact is established between the fixed contact piece 8 and the movable contact member 10, it will be energized to rotate the motor shaft 14 in a counter-clockwise direction and, through the gear-train 33—34—35—36 to simultaneously move the brush 7 in a clockwise direction. Similarly, when contact is established between 9 and 10, the motor will be energized to rotate said shaft in a clockwise direction and to simultaneously move the brush 7 in a counter-clockwise direction. The fixed contact pieces 8 and 9 are electrically insulated while the contact member 10 is fastened to

the periphery of a copper disc 11 and is electrically connected therewith. The axis of the disc 11, the purpose of which will be presently described, coincides with that of the motor shaft 14, said disc being independently pivoted at 12 and 13, Figure 2, and mechanically free to rotate in either direction except as limited by the fixed contact pieces 8 and 9, Figure 1. The circuit which energizes the motor to move the brush 7 in said counter-clockwise direction starts at battery 15, thence through the armature 2 and field winding 3 of the motor and wire 16 to the fixed contact piece 9 which, when engaged by the contact member 10, closes the circuit through the disc and a flexible connection 17 back to the battery. Similarly the circuit which energizes the motor to move the brush 7 in said clockwise direction starts at the battery 15, thence through the armature 2 and field winding 4 of the motor and wire 18 to the fixed contact piece 8 which, when engaged by the contact member 10, closes the circuit through the disc and the flexible connection 17 back to the battery.

The normal position of the contact member 10 which is carried by the disc 11 is midway between the fixed contact pieces 8 and 9. The contact member 10 is maintained in its normal position as illustrated by means of two electromagnets 21 and 22 both of which are in a fixed position and when energized react respectively with armatures 23 and 24. The armatures 23 and 24 are fastened to the disc 11 in the proper positions so that, when the magnet 21 is energized, its reaction with its armature 23 will tend to move the disc in a counter-clockwise direction, and when the magnet 22 is energized its reaction with its armature 24 will tend to move the disc in a clockwise direction. The magnets 21 and 22 are so designed that when the same amount of current flows through each of them, the resulting tendencies to move the disc in opposite directions will be equal thus causing the contact member 10 to assume its normal position in which position as previously stated said member is midway between the fixed contact members 8 and 9 and makes electrical contact with neither of them.

A second potentiometer consisting of the brush 25 and resistances 26 and 27 is electrically connected with the electromagnets 21 and 22 and with the potentiometer 5—6—7 through a battery 28 and wires 29, 30, 31 and 32, so that when the brushes 7 and 25 are in their midway positions as illustrated, the amount of current flowing through the magnet 21 will be the same as that flowing through the magnet 22 thus main-

taining a balanced condition under which both of the motor circuits will remain open. In other words when the brushes 7 and 25 are each in said midway position, the sum of the resistances 5 and 26 will equal the sum of the resistances 6 and 27, thus equalizing the amount of current which flows through the magnets 21 and 22. Under this condition the reaction between the magnet 21 and its armature 23 tends to rotate the disc in a counter-clockwise direction with a force equal to the reaction between the magnet 22 and its armature 24 which tends to rotate the disc in a clockwise direction, thus causing the contact member 10 to assume its normal position in which position of said member, neither of the motor circuits previously traced will be closed and the motor will remain idle.

It follows from the above that a change in the position of the brush 25 in a counter-clockwise direction to any new position such as 25a, 20 will increase the resistance 26 and decrease the resistance 27 thus increasing the amount of current flowing through the magnet 21 and decreasing the amount of current flowing through the magnet 22 thereby increasing the force of reaction between the magnet 21 and its armature 23, and decreasing the force of reaction between the magnet 22 and its armature 24. The dominating force of the magnet 21 will thus cause the disc 11 to move in a counter-clockwise direction to engage the contacts 9 and 10. The engagement of the contacts 9 and 10 closes the circuit which energizes the motor to rotate the motor shaft 14 in a clockwise direction and simultaneously, through the gear train 33-34-35-36, to move the brush 7 in a counter-clockwise direction. The motion of the brush 7 in this direction will obviously increase the resistance 6 and decrease the resistance 5 until the sum of the resistances 6 and 27 again equals the sum of the resistances 5 and 26 at which time the amount of current flowing through the magnet 21 will again be the same as that flowing through the magnet 22, the contact 10 will again have assumed its normal position as illustrated and the motor will cease to function. Similarly a change in the position of the brush 25 in a clockwise direction to any new position 25b will increase the resistance 27 and decrease the resistance 26 thus increasing the amount of current flowing through the magnet 22 and decreasing the amount of current flowing through the magnet 21 thereby increasing the force of reaction between the magnet 22 and its armature 24 and decreasing the force of reaction between the magnet 21 and its armature 23. The dominating force of the magnet 22 will now cause the disc 11 to move in a clockwise direction to engage the contacts 8 and 10, thereby closing the circuit which energizes the motor to rotate the motor shaft 14 in a counter-clockwise direction and simultaneously to move the brush 7 in a clockwise direction. The motion of the brush 7 in this direction will increase the resistance 5 and decrease the resistance 6 until the sum of the resistances 6 and 27 again equals the sum of the resistances 5 and 26 at which time the currents flowing through the two magnets 21 and 22 will again have the same magnitude under which condition the contact member 10 will again have assumed its normal position as illustrated and the motor will again cease to function.

It follows from the above that when the brush 25 is moved to any new position, the motor

will be energized to function in the proper direction to move the brush 7 to a corresponding position in which position as previously described the contact member 10 will assume its normal position as illustrated to deenergize the motor. It is obvious however, from the foregoing description that so long as the magnets 21 and 22 are unbalanced, so long will contact be established between contact member 10 and one or the other of the fixed contact pieces 8 and 9 thus causing the motor to function at full speed until the brush 7 has reached its balanced position in which position the current flowing through the two magnets 21 and 22 will be the same and the motor deenergized. The inertia of the motor will however cause the brush 7 to move beyond its balanced position thus, in the manner previously described, causing the contact member 10 to move beyond its normal position to engage the other fixed contact piece thereby reversing the motor with a speed sufficient to create an inertia that will move the brush 7 beyond its balanced position in the opposite direction thus causing the contact member 10 to move in the opposite direction sufficiently to again engage the fixed contact member 8. The inertia of the motor will thus cause a hunting action which for any fixed position of the brush 25 will cause the brush 7 to move back and forth through an angle depending upon the inertia involved. This action is obviously very objectionable and is prevented by means of a permanent magnet 19 which is fastened to the motor shaft 14 and is rotated by the motor in a clockwise direction when, in the manner described, contact is established between 9 and 10 and in a counter-clockwise direction when contact is established between 8 and 10. The magnet 19 is fastened to the motor shaft 14 in close proximity of the disc 11 by means of a hub 20. This magnet, which is rotated by the motor in one direction or the other depending upon which of the motor circuits is closed by the contact member 10, in combination with said disc and the contacts 8, 9 and 10 provides, as will be seen, the means for eliminating the aforesaid hunting action and therefore constitutes a very important part of this invention.

It is obvious that when the magnet 19 is rotated by the motor in either direction, eddy currents will be induced in the disc 11 which will react with the magnet to create a force or drag which tends to move the disc in the same direction; furthermore this force is a function of the speed of the magnet, the magnitude of which increases as the speed of the motor increases and decreases as the speed of the motor decreases until, when the magnet is at rest, said force will be zero. It follows therefore that when the brushes 7 and 25 are in any balanced position, as for example the midway positions illustrated, the balanced forces of the electromagnets 21 and 22 will maintain the contact member 10 in its normal position as illustrated, the motor will be deenergized and the magnet 19 which under this condition is at rest will have no influence whatsoever on the disc. On the other hand if the brush 25 is moved in a counter-clockwise direction to some new position 25a, the force of the reaction between the magnet 21 and the armature 23 will be decreased while the force of reaction between the magnet 22 and the armature 24 will be increased thus, in the manner previously described, causing the contact member 10 to engage the contact piece 8, energizing

the motor to rotate the magnet 19 in a counter-clockwise direction and simultaneously moving the brush 7 in a clockwise direction. Under these conditions the forces applied to the disc 11 will be threefold, viz the two opposing forces of the electromagnets 21 and 22, the latter dominating to establish contact between 10 and 8 to energize the motor in the proper direction to rotate the magnet 19 in a counter-clockwise direction, and the force of reaction between the magnet 19 and the eddy currents which are created in the disc just as soon as the magnet starts to rotate. The last mentioned force or drag on the disc is obviously a function of the speed of the magnet and will therefore continue to increase in magnitude in a counter-clockwise direction with the increasing speed of the motor until sufficiently large to overcome the unbalanced condition of the magnets 21 and 22 at which time contact between 10 and 8 will be broken and the motor deenergized. If during the period of time in which the magnet 19 has gained sufficient speed to break electrical contact between 10 and 8, the brush 7 has been moved sufficiently by the motor in a clockwise direction to balance the electromagnets 21 and 22, then the contact member 10 will remain in its normal position as illustrated. On the other hand if, during the period in which the magnet 19 has gained sufficient speed to break contact between 8 and 10, the brush 7 has not yet moved far enough to balance the magnets 21 and 22 then, after contact has been broken between 8 and 10 by the drag on the disc, the motor will merely slow down until the drag on the disc in a counter-clockwise direction as caused by the rotating magnet 19 has decreased to a point where the resultant force of the two electromagnets 21 and 22 again dominates sufficiently in a clockwise direction to reestablish contact between 8 and 10. This action will obviously repeat itself until the reaction of the electromagnet 21 with its armature 23 balances the reaction of the electromagnet 22 with its armature 24 at which time the contact member 10 will remain in its normal position as illustrated and the brush 7 will have assumed a new position corresponding to whatever new position into which the brush 25 might have been moved. In this connection it should be pointed out that for every revolution of the magnet 19 the brush 7 is moved a proportionate amount in the proper direction to balance the electromagnets 21 and 22 and therefore the resultant force of said magnets which tends to establish contact with one or the other of the fixed contact pieces 8 and 9 is progressively decreased. It therefore follows that as the brush 7 approaches the position in which the electromagnets 21 and 22 are balanced the resultant force of the two magnets 21 and 22 which establishes contact, not only becomes smaller and smaller but the required speed of the magnet 19 to create a drag of sufficient magnitude to break contact also becomes less and less so that as the brush 7 approaches a new position corresponding to any new position of the brush 25, the motor will continue to slow down until the brush 7 has reached its final position in which the contact member 10 will remain in its normal position as illustrated and further functioning of the motor will be impossible unless the brush 25 is moved to still another new position. The motor thus has two functions to perform; first, to move the brush 7 as required to balance the electromagnets 21 and 22 for any given position of 75

the brush 25; and second, to rotate the permanent magnet 19 with respect to the disc 11 to prevent overstepping or hunting. These two functions are performed simultaneously in the manner described thus causing the brush 7 to move rapidly when the electromagnets 21 and 22 are very much out of balance and gradually retarding the speed of the brush as it approaches the balanced position, the speed of the brush and the difference in the magnitude of the two forces exerted by the magnets 21 and 22 reaching zero at the same time.

Although the motor illustrated and described is a series wound motor with a separate field for each direction of rotation, it is obvious that any reversible motor may be utilized to accomplish the same results. Although, for the purpose of illustration, I have chosen to show an eddy current drag disc, it is obvious that any other form of drag created by the motor in its direction of rotation could be applied to accomplish the same results without in any way departing from this invention. Furthermore the motor which automatically moves the brush 7 to any corresponding position of the brush 25 might readily be energized by means of electronic tubes, the grid circuits of which could be regulated as required by means of the contacts 8, 9 and 10, or by any other electronic means capable of being controlled by a movable element subjected to the same influence as the element 10 herein described, without in any way departing from this invention.

I claim:

- 35 1. In a device of the class described, the combination with a reversible electric motor, and switching means for controlling its direction of rotation, including a movable contact element and two fixed contacts for alternative engagement therewith; of a member rockable about the axis of rotation of the motor and supporting the contact element to move the same therewith, said rockable member carrying a pair of diametrically disposed armatures, respective electromagnetic means juxtaposed to the armatures to move angularly the rockable member in accordance with the energization of the electromagnetic means, means to control the energization of said electromagnetic means, and means rotatable by the motor and associated with the rockable member to oppose its angular movement.
- 40 2. In a device of the class described, the combination with a reversible electric motor, and switching means for controlling its direction of rotation, including a movable contact element and two fixed contacts for alternative engagement therewith; of a member rockable about the axis of rotation of the motor and supporting the contact element to move the same therewith, said rockable member carrying a pair of diametrically disposed armatures, respective electromagnetic means juxtaposed to the armatures to move angularly the rockable member in accordance with the energization of the electromagnetic means, means actuated by the motor to control the energization of said electromagnetic means, means rotatable by the motor and associated with the rockable member to oppose its angular movement, and means for changing the energization of said electromagnetic means independently of the motor.
- 45 3. In a device of the class described, the combination with a reversible electric motor, and switching means for controlling its direction of rotation, including a movable contact element

and two fixed contacts for alternative engagement therewith; of a copper disc rotatable about the axis of rotation of said motor and supporting the contact element to move the same therewith between said two fixed contacts, said disc carrying 5 a pair of diametrically disposed armatures, respective electromagnetic means juxtaposed to the armatures to rock the disc in accordance with the energization of the electromagnetic means, means to control the energization of the electromagnetic 10 means, and magnetic means rotatable by the motor and associated with the disc to exert an eddy current drag thereon.

4. In a device of the class described, the combination with a motor and a metallic element rotatable thereby, of a circuit for energizing the motor to function in one direction, a second circuit for energizing the motor to function in the opposite direction, a contact arm fastened to the rotatable metallic element, a fixed contact piece 20 in the path of the contact arm which limits the rotation of the element in one direction and which when engaged by the contact arm closes the first circuit, a second fixed contact piece in the path of the contact arm which limits the rotation of the element in the opposite direction and which when engaged by the contact arm closes the second circuit, a movable magnet 25 driven by the motor for creating a magnetic drag on the element which when the motor functions in said one direction tends to move the contact arm away from the first contact piece and when the motor functions in the opposite direction tends to move the contact arm away from the second contact piece, means for applying a force to the element which tends to establish contact between the contact arm and the first contact piece, means for applying a second force to the element which tends to establish contact between the contact arm and the second piece, means 30 actuated by the motor for changing the ratio of the magnitude of said forces, and means for changing said ratio independently of said motor actuated ratio changing means.

5. In a device of the class described, the combination with a rotatable disc, of a contact member fastened to the periphery of the disc, a fixed contact piece in the path of the contact member for limiting its motion in a clockwise direction and which when engaged by the contact member establishes electric contact therewith, a second fixed contact piece in the path of the contact member for limiting its motion in a counter-clockwise direction and which when engaged by the contact member establishes electric contact therewith, a rotatable magnet located in proximity of the disc for creating an eddy current drag on the disc when the magnet is rotating, a motor for rotating the magnet, a circuit which is closed by contact between the contact member and the first fixed contact piece for energizing the motor to rotate the magnet in the proper direction to create a drag on the disc which tends to move the contact member away from the first fixed contact piece, a second circuit which is closed by 45 contact between the contact member and the second fixed contact piece for energizing the motor to rotate the magnet in the proper direction to create a drag on the disc which tends to move the contact member away from the second fixed contact piece, an armature fastened to the disc, an 50 electromagnet with which the armature reacts in the proper direction to establish contact between the contact member and the second fixed contact piece, a third circuit which includes a source of 55

electrical energy, a resistance, the electromagnet and a second resistance, a second armature fastened to the disc, a second electromagnet with which the second armature reacts in the proper direction to establish contact between the contact member and the first fixed contact, a fourth circuit which includes the source of energy, a third resistance, the second electromagnet and a fourth resistance, means actuated by the motor for changing the relative magnitudes of the first and third resistances, and independent means for changing the relative magnitudes of the second and fourth resistances.

6. In a device of the class described, the combination with a movable contact member, of a fixed contact member capable of being engaged by the movable contact member to close an electric circuit, a second fixed contact member capable of being engaged by the movable contact member to close a second electric circuit, an electromagnet which when energized tends to move the movable contact member into engagement with the first contact member, a second electromagnet which when energized tends to move the movable contact member into engagement with the second fixed contact member, means for energizing said electromagnets, a variable resistance for controlling the energy input to the first electromagnet, a second variable resistance for controlling the energy input to the second electromagnet, an electrical means in the first circuit for simultaneously increasing the first resistance and decreasing the second resistance, a second electrical means in the second circuit for simultaneously decreasing the first resistance and increasing the second resistance, means actuated by the first electrical means for creating an eddy current drag which tends to move the movable contact element away from the first fixed contact element, means actuated by the second electrical means for creating an eddy current drag which tends to move the movable contact element away from the second fixed contact element, and independent means for changing the ratio of said variable resistances.

7. The combination with a motor, of a circuit for energizing the motor to rotate in one direction, a second circuit for energizing the motor to rotate in the opposite direction, a movable contact member, means actuated by the motor for creating a drag which tends to move the movable contact member in the direction of rotation of the motor, a fixed contact which said movable contact member, when moved in said one direction, is capable of engaging to close the second circuit, electrical means for moving the movable contact member into engagement with this fixed contact member in opposition to the drag in said opposite direction, a second fixed contact which said movable contact member, when moved in said opposite direction, is capable of engaging to close the first circuit, and electrical means for moving the movable contact member into engagement with the second fixed contact in opposition to the drag in said one direction.

8. The means set forth in claim 7, with additional means for simultaneously electrically energizing both of said electrical means, independent means for changing the ratio of the electrical input to one of said electrical means with respect to that of the other, and means actuated by the motor for changing said ratio.

9. In a device of the class described, the combination with a reversible motor, of a circuit for energizing the motor to rotate in one direction,

a second circuit for energizing the motor to rotate in the opposite direction, an electromagnet which when energized tends to close the first circuit and open the second circuit, a second electromagnet which when energized opposes the first electromagnet and tends to close the second circuit and open the first circuit, means for energizing both electromagnets simultaneously, means actuated by the motor for creating a drag in one direction or the other depending upon the direction of rotation of the motor, means for applying the drag in said one direction to oppose the action of the first electromagnet and tending to open the first circuit, means for applying the drag in said other direction to oppose the action of the second electromagnet and tending to open the second circuit, means actuated by the motor for changing the ratio of energy input of the first electromagnet with respect to that of the second, and independent means for changing said ratio.

10. In a device of the class described, the combination with a reversible motor, of a circuit for energizing the motor to rotate in one direction, a second circuit for energizing the motor to rotate in the opposite direction, means actuated by the motor for creating an eddy current drag in the direction of its rotation, electrical means which tends to close the first circuit, means actuated by the drag in said one direction which tends to open the first circuit, a second electrical means which tends to close the second circuit, means actuated by the drag in said opposite direction which tends to open the second circuit, a third circuit which includes the first electrical means, a fourth circuit which includes the second electrical means, a source of electrical energy in both of said third and fourth circuits, a variable resistance in the third circuit, a second

variable resistance in the fourth circuit, means actuated by the motor for simultaneously changing both of said resistances, and independent means for simultaneously changing said resistances.

11. In a device of the class described, the combination with a movable contact member, of a fixed contact member for limiting the motion of the movable contact member in one direction, a second fixed contact member for limiting the motion of the movable contact member in the opposite direction, means for applying a force to the movable contact member in said one direction to cause its engagement with the first fixed contact member, means for applying a force to the movable contact member in said opposite direction to cause its engagement with the second fixed contact member, means for changing the ratio of the magnitude of the first force with respect to that of the second force, means for creating a magnetic drag, means for applying the drag to the movable contact member, an electric circuit which is closed by engagement of the movable contact member with the first fixed contact member, electrical means in said circuit for actuating said ratio changing means in one direction and simultaneously actuating said drag creating means to move the movable contact member away from the first fixed contact member, a second electric circuit which is closed by engagement of the movable contact member with the second fixed contact member, and a second electrical means in the second circuit for actuating said ratio changing means in the opposite direction and simultaneously actuating said drag creating means to move the movable contact member away from the second fixed contact member.

F. FREDERICK UEHLING.
